MACHINE FOR HOLDING PAPER

David E. Legge, Foxborough, Mass.

Application November 25, 1932

Serial No. 644,201

9 Claims. (Cl. 11—1)

This invention relates to a machine for firmly holding paper, and particularly sheets of paper to which gummed cloth or other material is to be attached at one edge to make it into pads or blocks.

Heretofore the sheets of paper have been held in permanent position by placing heavy weights on the top of the pile, which is quite commonly done today, although I am well aware that there are machines which are intended to hold paper; but which are not generally used because they are awkward and slow in operation.

One of my objects has been to provide a machine with mechanism that can be readily moved to operable position and quickly clamped down on the paper to be held regardless of the height of the stack of said paper.

Another object has been to so construct such a machine that it may serve as a truck on which to carry the paper away. Still another object has been to make my machine so simple in construction and easy in operation that it is economical to build and may be effectively used by a wholly unskilled person and one who is not strong enough to handle the heavy weights now commonly used.

The foregoing and other objects which will appear as the nature of the invention is better understood, may be accomplished by a construction, combination and operative arrangement of parts such as is disclosed by the drawing. The nature of the invention is such as to render it susceptible to various changes and modifications, and, therefore, I am not to be limited to the construction disclosed by the drawings; but am entitled to all such changes therefrom as fall within the scope of my claims.

In the drawing:

Figure 1 is a front elevation of my machine. Figure 2 is a side elevation of my machine showing a quantity of paper firmly held in position. Figure 3 is a plan view of the rear portion of my machine showing the brackets fastened thereto, between which the holding board is kept. Figure 4 is an enlarged fragmentary view partly in section illustrating in detail my clamping mechanism in operable position.

As illustrated my machine has a platform 1 for the supply of paper to rest upon, which platform is secured to a base 2. Said platform 1 and base 2 slant downwardly towards the rear as illustrated in Figure 2 of the drawing. Said base 2 is equipped with one or more wheels 3 and fastened to said base are sides 4 which also serve as handles, thereby making it possible to wheel my

machine around and thereby serve as a hand truck. On each side of my machine are vertical rods 5 fastened by brackets 6 to said sides 4 which rods serve as guides in sliding the clamping mechanism to operating position on them. The frame 60 of my machine is completed by a back 8 which as shown is composed of slats fastened to cross boards in the usual manner.

The operable holding means consist of arms 7 which are slidably mounted on said guide rods 5, 65 to which arms 7 are connected clamp members 9 by parts later explained. Said clamp members 9 are actuated by levers 10 which have a cam portion 11 at one end. An upright standard 12, having a vertical slot 24 therein, forms part of said clamp member 9 and extends upwardly into the head portion 13 of arm 7, being movable in said arm. A pivot pin 20 passes through said cam portion 11 of lever 10, being eccentrically positioned as shown in Figure 4, pivotally fastening 75 it to said clamp member head portion 13.

In said slot 24 is a spring member 22 which seats on a pin 23, which passes through said arm 7 and slot 24.

A supply of paper 16 is placed on said platform 1 and a board 14 placed on said paper. Said arms 7 are slid down on said rod 5 until they rest on said board 14. Said levers 10 are then pushed over rearwardly from their inoperable position which is illustrated by the lever 10 at the left in 80 Figure 1 of the drawings. This rotates the cam portion 11 so that its larger part forces said standard 12 downwardly and clamp member 9 to thereby tightly hold the stack of paper 16 while gummed cloth or other material is applied 85 to it. The downward movement of said standard 12 compresses said spring 22 on said pin 23, and upon the return of said lever 10 to its original position by pushing it forwardly, the tension of this spring 22 forces said standard 12 and clamp 90 member 9 upwardly, and all pressure on the board 14 and paper 16 is removed. The arms 7 may then be slid upwardly and swung to one side and the board 14 removed and slid in between brackets 15 attached to the back 8. Said board 14 is 95 preferably used so the clamping action will be distributed over the supply of paper being held, 100 and to protect it.

My machine may be grasped by said handles 4 and the paper moved around as on an ordinary 105 truck.

What I claim is:

1. A paper holding machine comprising means to support a supply of paper, rod means attached to said first-mentioned means, an arm slidably 110

mounted on said rod means, a clamping member embodying a standard movable in said arm, and a lever adapted to contact with said standard when actuated to thereby move said clamping member to clamping position.

2. A paper holding machine comprising means to support a supply of paper, rod means attached to said support means, clamping instrumentalities embodying an arm fastened to said rod means, a lever eccentrically mounted on said arm, and a clamping member connected to said arm adapted to be actuated by said lever.

3. A paper holding machine comprising means to support a supply of paper, rod means attached to said support means, clamping mechanism fastened to said rod means embodying clamping members and levers eccentrically mounted to said mechanism and adapted when actuated to move said clamping members to clamping position.

20 4. A paper holding machine comprising means to support a supply of paper, rod means attached to said support means, an arm slidably mounted on said rod means, a clamping member embodying a standard, said arm having provision to receive said standard therein, a lever having a cam portion pivotally and eccentrically mounted on said arm and so positioned with respect to said standard that actuation of said lever moves said standard.

30 5. A paper holding machine comprising means to support a supply of paper, rod means attached to said support means, an arm slidably mounted on said rod means, said arm carrying a clamping member embodying a standard, said standard having an opening therein, a spring in said opening, a lever eccentrically and pivotally mounted on said arm and adapted to be moved into contact with said standard and actuate said clamping member.

40 6. A paper holding machine comprising means to support a supply of paper, rod means attached to said support means, an arm slidably mounted on said rod means having an opening therein, said arm carrying a clamping member embodying a standard slidably in said opening in said arm, said standard having an opening therein, a spring

in said latter-mentioned opening, a seat member for said spring fastened to said arm, a lever having a cam portion eccentrically and pivotally mounted on said arm adapted to be moved into contact with said standard and actuate said clamping member.

7. A paper holding machine comprising means to support a supply of paper, rod means attached to said support means extending in an upright position, an arm slidably mounted on said rod means having an opening therein, a clamping member embodying a standard slidable in said opening, said standard having a slot therein intermediate its ends, a spring in said slot, a seat member for said spring extending through said slot and into said arm, a lever having a cam portion eccentrically and pivotally mounted to said arm, said lever being so positioned with respect to said standard that it is adapted to contact with said standard when actuated and move said standard downwardly.

8. A paper holding machine comprising means to support a supply of paper, guide mechanism attached to said means, an arm slidably mounted on said guide mechanism having provision to slidably receive a standard, a clamping member embodying a standard slidably mounted in said arm, said standard having a slot therein, a spring in said slot, a pin extending through said slot and into said arm, said spring resting on said pin, a lever having a cam portion eccentrically and pivotally mounted to the upper portion of said arm, said cam portion of said lever being adapted when actuated to contact with said standard and force it downwardly thereby moving said clamping member to clamping position and compressing said spring.

9. A paper holding machine comprising means to support a supply of paper embodying wheel means and side members with their ends formed into handles, guide means attached to said side members, clamping mechanism slidably mounted on said guide means embodying a lever adapted to actuate said clamping mechanism to clamping position.
